CLAIM

The ornamental design for a note dispenser, as shown and described.

DESCRIPTION

FIG. 1 is a perspective view showing the new design for a note dispenser;

FIG. 2 is a front view thereof;

FIG. 3 is a left side view thereof;

FIG. 4 is a right side view thereof;

FIG. 5 is a top view thereof;

FIG. 6 is a rear view thereof;

FIG. 7 is a bottom view thereof; and,

FIG. 8 is a perspective view thereof showing the note dispenser with a note pad.

The portions of the note dispenser in FIGS. 1–5 and 8 shown in broken lines are included to show features that form no part of the claimed design.

1 Claim, 4 Drawing Sheets(56)
